UNITED STATES PATENT OFFICE.

MORRIS C. CLARK, OF LOUISVILLE, KENTUCKY.

DOOR CLOSER AND CHECK.

1,046,556.

Specification of Letters Patent. Patented Dec. 10, 1912.

Application filed August 29, 1911. Serial No. 646,693.

To all whom it may concern:

Be it known that I, MORRIS C. CLARK, citizen of the United States, residing at Louisville, in the county of Jefferson and State of Kentucky, have invented certain new and useful Improvements in Door Closers and Checks, of which the following is a specification.

My invention comprehends certain new and useful improvements in door closers and checks, and has for its main object to provide a simple door closer easily adjustable to the weight of the door.

Another object is to provide a door closer and check which can be attached to doors of varying weights from a solid door to a light screen door.

A further object is to provide a door closer of this kind so constructed that it can be manufactured at minimum cost and its simplicity will insure its continual operation without attention.

With these and other objects in view as will more fully appear as the description proceeds, the invention consists in certain constructions, arrangements and combinations of the parts that I shall hereinafter fully describe and claim.

For a full understanding of the invention reference is to be had to the following description and accompanying drawing in which:

Figure 1, Sheet 1, is an elevation of the device operatively connected to a door casing and a closed door, the oscillating buffer being in its normal position; Fig. 2 is a plan view of the same; Fig. 3 is an elevation of the device operatively attached to a door casing and a partly closed door, the actuating arm of the device being shown only in part, and the oscillating buffer being in a raised position; Fig. 4, Sheet 2, is a vertical section on the line A—B of Fig. 3; Fig. 5 is an enlarged perspective view of the trip arm or oscillating buffer; Fig. 6 is a similar view of the trip arm actuating spur; Fig. 7 is a perspective view of the device with the operating mechanism removed.

Corresponding and like parts are referred to in the following description and indicated in all the views of the accompanying drawings by the same reference characters.

Referring to the drawings, the numeral 1 designates a casing provided with an attaching plate 2 for securing the device to a door casing M. A vertically disposed shaft

3 passes through the casing 1 and is journaled therein, being encircled by a coiled spring 4 which is attached at its opposite ends to the inclosing casing and said shaft. 60 An angular actuating member 5 embodying a forked end 5^a and a shank 6 is mounted on the upper and lower ends of the shaft 3 through the forked end 5^a. The upper forked member 5^a has its bearing on a fixed 65 inclosing plate 7 of the casing 1, and above this member on the shaft 3 a notched wheel 8 is rigidly mounted and is engageable by a pawl 9 of the upper fork member 5^a, whereby the tension of the spring 4 may be easily 70 adjusted according to the weight of the door to which the device is attached.

Connection is established between the actuating arm 5 and the door N through a clip 10 formed with looped ends slidably 75 mounted on the shank 6, said clip being further provided with a lug 11 by which it is pivotally attached to an angular plate 12 secured to the door.

In order to check the closing movement 80 of the door a horizontally disposed ledge 13 is formed between the casing 1 and the attaching plate 2 and is provided with a lug 13^a on which an oscillating, preferably resilient, arm 14 is pivoted intermediate its 85 ends, the longer end of said arm being formed with a return bend 14^b which encircles a buffer 15, and the shorter end 14^b being engageable with a spur 16 secured to the actuating arm 5 and projecting laterally 90 therefrom. A fixed buffer 17 is securely fastened to a boss 18 which is provided on the attaching plate 2, said buffer 17 being in the present instance disposed just above and at the inner side of the oscillating arm 95 14, as clearly illustrated in the drawing.

From the foregoing description in connection with the accompanying drawing, the operation of my device will be apparent. The tension on the spring 4 is adjusted 100 through the notched wheel 8 to suit the weight of the door and is maintained in this adjustment by engaging the pawl 9 with said wheel. Upon the door N being opened the clip 10 slides upon the shank 6 and the 105 actuating arm 5 rotates with the shaft 3 against the tension of the spring 4. As soon as the door is released the tension of the spring 4 operates upon the actuating arm through the shaft 3, the wheel 8 and the 110 pawl 9, thus forcing the door to close. Just before the door N completely closes the

under side of the spur 16 strikes the shorter end 14^b of the arm 14 and depresses the same, whereby the longer end of the said arm is elevated so that the buffer 15 is brought into the path of movement of the intermediate portion of the member 5. When the door N closes the member 5 strikes the buffer 15 and the force of impact from the door is broken. In the meantime the 10 end portion of the spur 16 passes beyond the inner edge of the arm 14 so that the shorter end 14^b is above the intermediate portion of the spur 16. When the door N rebounds the buffer 15 is released so that it falls by 15 gravity, carrying down with it the longer end of the arm 14 so that the shorter end 14^b is above or at the same level as the upturned end of the spur 16. When the door N again moves slowly to its closed position 20 the member 5 comes in contact with the buffer 17 and thus in the final closing of the door its movement is resiliently checked.

Having thus described the invention what is claimed as new is:

25 1. A door closer and stop comprising an actuating arm, means for operatively connecting said arm to a door, an arm pivoted adjacent the door, a buffer carried by said arm, a spur carried by the actuating arm 30 and adapted to tilt said pivoted arm and thereby move the buffer into the path of movement of the actuating arm, and a second buffer arranged at one side of the said pivoted arm to receive the impact from the 35 door after its rebound from the buffer on the pivoted arm.

2. A door closer and stop comprising an actuating arm, means for operatively connecting the same to a door, an arm pivoted 40 adjacent the door and provided with a buffer, and a rigid spur carried by the actuating arm and adapted to tilt the pivoted arm to move the buffer into the path of movement of the actuating arm, said actuating arm being shaped to clear said pivoted arm in the final closing movement of the door.

45 3. A door closer and stop comprising a spring-controlled actuating arm, means for

connecting said arm to a door, a spur rigid 50 with and depending from the actuating arm, and an oscillating buffer adjacent the door and arranged to be engaged by said spur whereby it will be swung into the path of movement of the actuating arm. 55

4. A door stop comprising an oscillating arm mounted on the door casing, a buffer carried by said arm, a spur connected to the door and arranged to engage the oscillating arm and move the buffer to a position to 60 initially interrupt the closing of the door, and a stationary buffer arranged on the door casing adjacent the first-mentioned buffer to receive the impact of the door after the rebound and on its final closing move- 65 ment.

5. A door stop and closer comprising a casing having an extended attaching plate adapted to be secured to a door casing, a spring-controlled shaft journaled in said 70 casing, an actuating arm rigid with said shaft and having a sliding connection with the door, an oscillating buffer mounted on said attaching plate, and means on the actuating arm to engage said buffer and swing 75 the same into the path of the actuating arm on the closing movement of the door.

6. A door stop and closer comprising a casing having an extended attaching plate adapted to be secured to a door casing, a 80 spring-controlled shaft journaled in said casing, an actuating arm rigid with said shaft and having a sliding connection with the door, an oscillating buffer mounted on said attaching plate, means on the actuating 85 arm to engage said buffer and swing the same into the path of the actuating arm on the closing movement of the door, and a fixed buffer on the attaching plate adjacent the oscillating buffer and in the planes of move- 90 ment of said buffer and the actuating arm.

In testimony whereof, I affix my signature in presence of two witnesses.

MORRIS C. CLARK. [L.S.]
